UNITED STATES PATENT OFFICE.

MALCOLM D. MALCOMSON, OF WEST ORANGE, NEW JERSEY, AND CHRISTOPHER A. KETCHEN, JR., OF WATERBURY, CONNECTICUT.

HANGER OR WALL-HOOK.

1,248,363.

Specification of Letters Patent. Patented Nov. 27, 1917.

Application filed September 26, 1916. Serial No. 122,189.

To all whom it may concern:

Be it known that we, MALCOLM D. MALCOMSON and CHRISTOPHER A. KETCHEN, Jr., both citizens of the United States, MALCOLM D. MALCOMSON residing at West Orange, county of Essex, State of New Jersey, and CHRISTOPHER A. KETCHEN, Jr., residing at Waterbury, county of New Haven, State of Connecticut, have invented certain new and useful Improvements in Hangers or Wall-Hooks, of which the following is a description, reference being had to the accompanying drawings.

The invention relates to that class of devices which are attached to a side wall to provide a means of hanging various articles thereon.

It comprises an article made from one length of material formed up so as to provide a member to serve as a fastening pin which is adapted to be driven into the wall, and a hook portion terminating below the fastening pin but not resting directly on it.

The particular construction by which this result is accomplished will be more fully set forth in the following description and shown in the drawings.

Figure 1 is a plan view of a blank for a hanger made from flat material.

Fig. 2 is a perspective view of hanger bent up from Fig. 1.

Fig. 3 is a side view of Fig. 2.

Fig. 4 is a view of the hanger made from round metal and Fig. 5 is a modification.

As will be seen by the drawings our device is formed up from one piece of metal, including the pin which is to enter the wall. This is so even when the hanger is made of flat metal, as is shown by the blank in Fig. 1. In this figure A represents the body of the device and B the securing pin. When made of flat metal a longitudinal central slot C is formed in the body, through which the pin B will project when the hanger is formed up for use.

In case the device is made from round steel or wire, provision is made for the central slot C by looping the wire at this point,

care being taken that the loop C, through which the pin B passes is longitudinally 50 oblong in shape so its vertical dimension will extend above the pin B. The loop however does not interfere with the body of the hanger being substantially straight and lying flat against the wall.

In Fig. 2 it will be seen that the upper terminal end of the slot C is some distance above the pin B. By this construction the pin does not come in contact with the metal at the upper end of the slot B, or bear the 60 direct weight of the hanger at this point. The body A is formed straight between the top at a and the point b at the bottom where it bends to form the hook D. This provides for the back of the hanger lying against the 65 wall for its entire length.

From the turning point a the metal extends a distance downward and is again bent at c, so the remaining part, which forms the pin B will pass the straight body portion 70 A at an angle.

At d, we preferably make a second bend providing double thickness of metal in order to form a head e and strengthen the pin at this point where it receives the stroke of a 75 hammer when being driven into the wall W. When the body is composed of flat metal, with a narrow central slot, and the pin end portion B is reduced in size to allow it to pass through the slot, the wider part of the 80 material should be bent over as shown in Fig. 2. This construction avoids danger of weakness which might arise from bending the reduced metal where it joins the wider part.

It will be understood that the weight sustained by the hook D is transmitted to a pull on the straight body A and distributed from the point a, hence a downward pressure on the hook tends to wedge or jam the 90 upper end of the body A against the wall.

What we claim as our invention is,

A hanger composed of a continuous piece of metal, comprising a central straight body portion the lower end of which is bent up 95 into a rigid hook element, the opposite end

of said continuous piece forming a pin element which is bent outward and inward, on the hook side, making with the central central straight body portion, a triangle 5 with the pin portion thereof bent upon itself to form a driving head, said pin element crossing the central straight body near its

center at an angle and extending to the side thereof opposite the hook, sufficient to form a projection to pierce the wall, substantially 10 as shown and described.

MALCOLM D. MALCOMSON.
CHRIS. A. KETCHEN, JR.

Copies of this patent may be obtained for five cents each, by addressing the "Commissioner of Patents, Washington, D. C."

It is hereby certified that in Letters Patent No. 1,248,363, granted November 27, 1917, upon the application of Malcolm D. Malcomson, of West Orange, New Jersey, and Christopher A. Ketchen, Jr., of Waterbury, Connecticut, for an improvement in "Hangers or Wall-Hooks," an error appears in the printed specification requiring correction as follows: Page 2, line 4, strike out the word "central"; and that the said Letters Patent should be read with this correction therein that the same may conform to the record of the case in the Patent Office.

Signed and sealed this 12th day of February, A. D., 1918.

[SEAL.]

J. T. NEWTON,

Commissioner of Patents.
